UNITED STATES PATENT OFFICE.

MARGARET M. FLAMMER, OF BALBOA, CANAL ZONE.

PICTURE AND DESIGN MADE FROM DRY EARTHS AND PROCESS OF MAKING THE SAME.

1,255,001.

Specification of Letters Patent. Patented Jan. 29, 1918.

Application filed November 10, 1915. Serial No. 60,755.

To all whom it may concern:

Be it known that I, MARGARET M. FLAMMER, a citizen of the United States, residing at Balboa, Canal Zone, have invented certain new and useful Improvements in Pictures and Designs Made from Dry Earths and Processes of Making the Same, of which the following is a specification.

My invention relates to a novel method of producing pictures and designs in colors and to the products of such process. In executing my invention I employ pulverulent earths of different colors and by the proper manipulation and handling of these I produce pictorial effects that are artistic and pleasing as well as novel. It is well known that the earths, including in that term sands, clays, soils, etc., are in their natural condition of many colors, from the most brilliant in hue to those that are somber in tone, and I avail myself of this fact in the execution of my invention, as the color effects of the pictures and designs I produce are secured by the use of different earths in their natural colors.

In practising my invention earths of different colors are secured, sifted to remove all coarser particles, and thoroughly dried. From these colored earths in a pulverulent and preferably dry condition I build up a picture, by arranging the earths of different colors in masses between confining surfaces, one at least of which is transparent, arranged close together. The earths are arranged and packed between these surfaces tightly so that when the space between them is filled no movement of the particles takes place. It is evident that by the method described true pictures with light and shade, and when desired, with color may be produced by means of the colored earths used, according to the skill of the workman or artist using the process.

In order to have a better understanding of my invention I have illustrated it in the accompanying drawings, in which—

Figure 1 is a plan view of a framed picture made according to my invention.

Fig. 2 is a transverse sectional view of the picture taken on the line X—X of Fig. 1;

Fig. 3 is a top plan view of a hollow retainer, of cylindrical form, for the earths used in making a picture or design; and

Fig. 4 is a vertical section taken on the line Y—Y of Fig. 3.

The view shown in Fig. 1 represents a

tract of country, somewhat broken in the foreground and gradually ascending toward a mountain that appears in the distance. To the right of the mountain is a lake surrounded by hills, the outlet of which flows down a valley shown at the extreme right. Above all is the sky in which are floating clouds. The effect of the broken surface of the ground in the fore of the picture, that is, in the lower part thereof, is produced by bands and masses of color secured by the use of selected colored earth artistically deposited, both as to place and quantity. The colors here commonly employed would be browns, greens and reds. In producing the mountain, greens may be used if it is to be represented as clothed with verdure, or brown in various shades if a bare mountain is to be represented. The water of the lake may be represented by the use of white or light green or blue, the sky by light gray or blue sand or earth, and the clouds in the sky by white.

The earths are arranged in a thin layer between a front wall 2, which is transparent and constitutes the covering sheet of the picture, and a back wall 3. I prefer that the two walls should be formed of an integral mass of glass united at the bottom as at 4. Between these walls or plates is the narrow space 5 into which the earths are packed, they being introduced through the opening at the top between the plates 2 and 3. After the picture has been formed and the chamber 5 filled, it is closed by a cap piece 6. The retainer thus formed may then be surrounded by a suitable frame 7. I do not wish to be limited to making the retainer integral, or to having the plates 2 and 3 of the same material, although I prefer the arrangement shown.

In Figs. 3 and 4 I have illustrated a hollow cylindrical form of retainer for the colored earths from which a picture or design is to be produced. It consists of an outer cylindrical wall 8, and an inner cylindrical wall 9 concentric therewith, between which walls is the space 10 into which the earths are placed and packed. One end of the cylinder 8 is open, exposing the space 10 for filling. This open end is closed, after the retainer has been filled, by a cap 11. The end of the inner concentric cylinder 9 nearest the cap-closed end of the cylinder 8 is closed by an integral portion 12, preferably dome-shaped. At the end of the retainer

2
opposite that closed by the cap 11 the two cylinders are united, as represented at 13, and the central space inclosed by the inner cylinder is left open, as indicated at 14.

5 By means of a retainer such as shown in Figs. 3 and 4 a picture or design may be executed that can be viewed from the outside, through the cylinder 8, or from the inside, through the cylinder 9, it being understood 10 that both retaining walls, 8 and 9 in this form of retainer are transparent.

I am aware that the practice of displaying sands and earths of various colors and natures by arranging them in strata or 15 layers within glass tubes or jars is old; but so far as I am aware earths of various colors, in dry pulverulent form, have never been employed to produce artistic designs or pictures such as I have produced and 20 have herein described and illustrated.

I am also aware that pulverulent ore, earths, glass and similar material have been used in making cabinet jewelry, mosaics and ornamental glass work, and that in the 25 manufacture of such articles, where the pulverulent materials referred to are used, it has been the practice to subdivide the space to be occupied by the finished product into a number of relatively small compartments 30 by means of partitions of one sort or another, and to fill these compartments with the pulverulent material employed, each compartment usually being filled with material of uniform kind or color. But my invention, both in the process or method of 35 operation and the product thereof as herein described, is radically different from the methods of operation and the products that have just been referred to. In operating ac- 40 cording to my invention, the colored pulverulent earths are arranged in a free or undivided space, so that the arrangement of the earths giving the desired pictorial effects is entirely undetermined by partitions 45 or mechanical separating means, and is dependent entirely upon the one practising the

invention. I can thus produce real pictures, true in their effects to life, rather than conventional designs, which are the result of the processes to which I have referred. 50

In practising my invention, it is often desirable to use a minute quantity only of an earth of a particular color, as for instance, to show a small cloud in the sky, a minute 55 lake in the distance, or a projecting rock in a field in the foreground, or the like. This is entirely feasible in using my invention, but the results attained thereby could not be produced by the use of colored earths in 60 practising the older methods to which I have referred.

What I claim is:—

1. The herein described method of making pictures and colored designs which consists in arranging in a free, undivided space colored earths in pulverulent condition to produce the desired lights, shades and pictorial effects, compacting the earths as arranged, and confining them by a transparent retainer. 65

2. The herein described method of making pictures and colored designs which consists in arranging pulverulent colored earths in a thin layer between confining walls in a 75 free, undivided space to produce the desired lights, shades and pictorial effects, one of the walls being transparent, and compacting the earths as arranged. 70

3. A picture the shaded and colored portions of which are formed from colored earths arranged to produce the desired pictorial effect, and confined in a free, undivided space between retaining surfaces, one of which is transparent. 80

4. A picture the shaded and colored portions of which are formed from dry pulverulent colored earths arranged in a thin layer undivided to produce the desired effect, such layer being confined between retaining surfaces, one of which is transparent. 90

(Mrs.) MARGARET M. FLAMMER.
